UNITED STATES PATENT OFFICE.

EDWARD P. NOYES, OF WINCHESTER, MASSACHUSETTS, ASSIGNOR TO CHARLES F. BROWN,
TRUSTEE, OF READING, MASSACHUSETTS.

STORED-PRESSURE MOTOR-STARTING DEVICE.

No. 880,815.

Specification of Letters Patent.

Patented March 3, 1908.

Application filed December 28, 1906. Serial No. 349,822.

To all whom it may concern:

Be it known that I, EDWARD P. NOYES, a citizen of the United States, residing at Winchester, in the county of Middlesex and State 5 of Massachusetts, have invented certain new and useful Improvements in Stored-Pressure Motor-Starting Devices, of which the following is a specification.

This invention relates to starting-devices 10 for motor apparatus employing an internal-combustion prime-motor and a secondary power-delivering motor of the steam-engine, compressed-air engine, or similar type.

The object of the invention is to dispense 15 with auxiliary engines or auxiliary valve-mechanism which has heretofore been found necessary in starting most internal-combustion engines on the stored-pressure plan. In place of such auxiliaries I make use of the 20 fluid-receiving and power-delivering engine which is a part of the motor system itself, and temporarily connect the shaft of this engine with the shaft of the internal-combustion motor and propel the latter under the 25 impulse of the former by means of stored compressed-air or other pressure-fluid used in the power-delivering engine until the internal-combustion motor has assumed its own normal functions and becomes self-running, whereupon the power-delivering engine 30 may be disconnected from the internal-combustion prime-motor and connected with the machinery which it is intended to drive under the impulse of pressure-fluid supplied by said 35 prime-motor.

The accompanying drawing shows in Figure 1 a sectional view of an automobile vehicle having a motive plant equipped with my improved stored-pressure starting arrangements. Fig. 2 represents an axial section of 40 the clutch mechanism.

As shown in the drawings the prime-motor unit includes an internal-combustion motor 1 of the explosion type and an air-compressor 45 2 connected to be driven by said motor and adapted to furnish the first stage of compression to an air-charge which is further compressed on the compression-stroke of motor 1.

3 is a fuel-carbureter operating under compressed-air pressure for supplying an explosive charge to the motor 1, and 4 is the compressed-air line which leads from compressor 2 to motor 1 and also leads to an air-storage tank 5 whose inlet is equipped with a manu- 55 ally-operable stop-valve 6. In the air-line 4

is an intercooler 7 of the automobile "radiator" type and the explosion-engine 1 may have suitable arrangements (not shown) of the usual character for cooling its jacket water. The motor 1 is adapted to operate under maximum compression and explosion pressures greatly exceeding those in use with simple explosion-engines.

The exhaust gases from the explosion-motor 1 pass through a discharge-pipe 8 to a fluid-receiving and power-delivering engine 9 of the steam-engine type, adapted to be coupled with the road-wheels 10 of the automobile or with any other machinery or apparatus driven by the motor system, this engine 9 normally running independently of the prime motor 1, that is without a mechanical driving connection between the two. A water-vaporizer 11 is shown associated with the discharge-conduit 8 for partly converting the high-temperature heat of the exhaust into steam-heat for use in the engine 9. At 12 is the manually-operable throttle admission-valve for engine 9. Engine 9 may also receive supplies of unburned compressed-air from the compressor 2 by way of the storage-tank 5 and a manually-operable throttle-valve 13, or by any suitable conduit connection from the compressor, the system as shown thus having some characteristics 85 of a pure compressed-air motor-and-transmission plant which I include within the scope of my invention although such a plant is inferior to one in which the internal-combustion prime-motor burns a part or at times all of the 90 air furnished by the compressing department and transmits its exhaust under pressure to operate the receiving-engine. I may use any suitable form of internal-combustion prime-mover adapted to furnish a substantial proportion of power through its exhaust to operate the engine 9, which latter also may be of any suitable construction.

The engine 9 as here shown, being of the reciprocating steam-motor or compressed-air-motor type, has valve arrangements adapting it to be operated by stored compressed-fluid without using an auxiliary valve-gear, and to use the engine 9 for starting the explosion-motor 1. I temporarily disconnect 105 engine 9 from its load or driven machinery and connect it with the prime-motor 1. A positive clutch 14 is shown to couple and uncouple the engine 9 with the road-wheels 10 of the automobile, and a similar clutch 15 is 110

shown for coupling and uncoupling engine 9 with the prime power-unit which includes explosion-motor 1 and compressor 2. The shaft of motor 9 is of course separate from 5 the shaft of motor 1 and from the propeller-shaft of the vehicle as indicated in Fig. 2, but is connectible with either one or the other by means of the clutches. These clutches might operate independently of each other 10 but I have shown them interconnected through suitable rockers 16 and a rod 17 with an operating lever 18 by means of which, owing to the reciprocal connection of the clutches, each clutch may be thrown into 15 gear by a movement which throws the other clutch out of gear. Thus when the engine 9 is connected with motor 1 and compressor 2 through the clutch 15, it is disconnected from its load by the opening of clutch 14, where- 20 upon the valve 13 may be opened to admit stored compressed-air from tank 5 into the engine 9 and cause it to drive and start the explosion-engine 1. At such a time the re- 25 sistance of compressor 2 may be temporarily relieved or mitigated by any suitable arrangement which would be provided by a skilled mechanic. When the motor 1 has been thus started, an opposite shifting of the clutches will disconnect engine 9 from motor 1 and 30 reconnect it with its load through clutch 14, whereupon the power-plant may assume its normal condition of operation in which the engine 9 is driven by pressure-fluids received from motor 1 and compressor 2.

35 I do not confine myself to compressed-air as the stored fluid for use in starting but may store burned gas under pressure from the internal-combustion motor, an expedient already familiar in the art. For allowing the 40 motor 1 to run while the motor 9 is stopped, a suitable disposition may be made of the exhaust from motor 1 but being unnecessary to an understanding of my present invention, no means to this end is illustrated.

45 I do not claim broadly, irrespective of the novel starting arrangements above described, the internal combustion motor system here disclosed, compounded in both its compression and expansion and employing a low- 50 pressure expansion engine mechanically-dis- severed from the high-pressure combustion-engine.

Where the nature of the external load admits, as for example in a flying machine or 55 a motor boat, it may be preferred to omit the clutch 14 and leave engine 9 at all times connected with its load. I also wish to make

it plain that various forms of clutching devices known to the art may be used in place of the specific ones illustrated and it is not 60 essential, for example, that the clutching device located at 15 shall be of a character requiring it to be actuated by an operator.

I claim:

1. In a compound motor system, the combination of a high-pressure internal-combustion prime-motor adapted to drive the external load indirectly through the medium of exhaust pressure-fluid, an independently-running low-pressure engine operated by the 70 pressure of the exhaust from said prime motor, means for storing the pressure fluid supplied by said prime motor and for admitting it to the low-pressure engine, and means for temporarily connecting the low-pressure 75 engine to drive the prime motor.

2. The combination of an internal-combustion motor, an independently-running receiving-engine operated by pressure-fluid supplied by said motor, means to store the 80 fluid under pressure to furnish a reserve for starting said receiving-engine, means to couple and uncouple said engine with its external load, and means to couple and uncouple said engine with the internal-com- 85 bustion motor.

3. A motor system comprising an internal-combustion motor and connected charging-air-compressor therefor together constituting a prime mover, a receiving-engine supplied by pressure-fluid from said prime-mover for driving the external load, means for storing the pressure-fluid to start the receiving-engine, a separable coupling between the receiving-engine and the prime-mover for 90 driving the latter by means of the former, and a separable coupling for connecting the receiving-engine with its external load and disconnecting it therefrom.

4. The combination of an internal-com- 100 bustion motor, an independently - running receiving - engine driven by pressure - fluid supplied by said motor, and reciprocally-act- ing clutches for connecting said receiving- engine alternatively with said internal-com- 105 bustion motor and with the external load.

In testimony whereof I have hereunto set my hand in the presence of subscribing witnesses, the 21st day of December, 1906.

EDWARD P. NOYES.
